EXTRACTIVE DISTILLATION OF AROMATICS

Frank S. Bondor, Wilmington, Del., and Edward H. Lebeis, Jr., Media, Pa., assignors to Houdry Process Corporation, Wilmington, Del., a corporation of Delaware

Application June 25, 1953, Serial No. 364,221

14 Claims. (Cl. 202—39.5)

The present invention relates generally to the separation, concentration and/or purification of aromatic hydrocarbons and is particularly concerned with improvements and methods for the recovery of mono-nuclear aromatic hydrocarbons such as benzene, toluene and xylenes from their admixtures with non-aromatic hydrocarbon components, e. g., in a naphtha fraction.

Hydrocarbon distillates boiling in the range of gasoline and naphtha from various sources and particularly such distillates obtained by catalytic reforming of naphtha comprise aromatic hydrocarbons in admixture with naphthenes and paraffins having boiling points very close to those of the aromatic components of the distillate, which renders the separation of the aromatic components by ordinary methods of fractional distillation extremely difficult or impossible. Moreover, certain of these components may form azeotropes with the aromatic hydrocarbon desired to be separated. Among the various separation techniques which have been tried with varying degrees of success there are included: liquid solvent extraction, selective azeotropic distillation, selective chromatographic adsorption, and extractive distillation. The present invention is concerned with improvements in processes involving the last-named type of operation, which type of process offers considerable flexibility and other advantages particularly from the standpoint of adaptability to different types of distillates as well as those of different boiling ranges.

The extraction of benzene from hydrocarbon fractions containing the same has been of increasing importance in recent years because of continued demands for this material for use as such or as an intermediate in numerous industrial processes. Also, with the increased production of reformed naphtha of desirably high aromatics content, the need for efficient methods for separation and recovery of benzene, and of other individual mono-nuclear aromatic hydrocarbons, has also increased. The improved method of the present invention is applicable to the recovery of benzene as well as to the recovery of toluene or xylenes (including ethyl benzene).

The more typical contaminants found associated with benzene in a benzene cut derived from a catalytically reformed naphtha include methylcyclopentane, which is generally present as the predominating contaminating naphthene, and various paraffins, including n-hexane, 2-methyl-hexane, methylpentanes and dimethylpentanes. An agent having high selectivity in the separation by extractive distillation of methylcyclopentane from benzene as well as in the separation of usually occurring C₆ and C₇ paraffins from benzene would obviously be desirable for use in processes involving benzene recovery.

The extractive distillation operation above described is based on the principle that the extractive distillation solvent effectively alters the activity coefficient of one or more components of the feed to render the same less or more volatile, and since the relative volatility of the contaminating naphthenes and paraffins as compared with benzene (or methylated benzene) is greater in the pres-

2

ence of the solvent, a higher degree of separation is possible than that obtained by ordinary methods of fractional distillation.

In the accompanying drawing the flow sheet includes 5 sufficient information to be self-explanatory.

In accordance with the present invention a mixture of aromatic and non-aromatic hydrocarbons, such as a closely cut naphtha fraction containing one of the mono-nuclear aromatics, is subjected to extractive distillation in 10 the presence of a butanediol or butylene glycol solvent, particularly one of the group comprising 2,3-butanediol and 1,3-butanediol, with the separation of a vapor overhead concentrated in non-aromatic contaminants and a liquid bottoms fraction containing the solvent concentrated with aromatic hydrocarbons.

In a method of this type, it is desirable that the solvent employed is higher boiling than the highest boiling component of the feed and that the boiling point of the solvent is high enough to allow easy separation in the aro- 20 matics stripper and low enough to permit reasonable reboiler temperatures. In this and other respects the butylene glycols or butanediols have proved well suited, and this is particularly the case with those of the group comprising 2,3-butanediol and 1,3-butanediol, all the 25 more as they are also commercially available. Both these compounds boil higher than the highest boiling xylene, ortho-xylene (144.4° C.), viz., at 182° C. and 204° C., respectively, so that the same solvent may be used for xylene separation as well as for benzene and toluene 30 separation from non-aromatic hydrocarbons. Of these butanediols, the 2,3-isomer is of primary importance, particularly as its boiling point, while high enough for the indicated purpose is considerably lower than that of the 1,3-isomer, whereby the use of correspondingly lower 35 reboiler temperatures is made possible.

The miscibility of the said butanediol isomers with non-aromatic hydrocarbons, however, is limited, particularly with respect to methylcyclopentane and 2,4-di- 40 methylpentane which are among the main contaminants of the aromatics to be recovered by the present process. This miscibility is still less for the 1,3-isomer than for the 2,3-isomer, the activity coefficient of which, moreover, is more favorable than that of the 1,3-isomer. On the other hand, in an extractive distillation column, the 45 concentration of nonsolvent in the single phase liquid on the trays should be as high as practical to give good throughput, but not so high as to reduce the relative volatility. An economic optimum value often used is about 30% non-solvent and 70% solvent. On the top 50 tray of the extractive distillation section, the liquid would then be composed of 70% solvent and 30% naphthenes and paraffins. That high a concentration of naphthenes and paraffins, however, cannot be attained with the use 55 as solvents of one of the two isomeric butanediols here in question. For this reason a secondary solvent or solubilizer is added in accordance with the present invention for increasing the solubility of the naphthenes and paraffins.

A small amount of this solubilizer is generally sufficient, while a greater amount thereof will not be harmful if the added solubilizer also improves the relative volatilities of non-aromatics to aromatics. The system can be operated in continuous manner by charging the solvent to the upper part of a fractional distillation tower and 60 bringing in the hydrocarbon feed to be separated or purified near the middle of the tower. The resulting liquid fraction comprising the solvent and aromatics is fed to a stripper for separation and the solvent stripped of aromatics recirculated to the extraction tower.

While numerous solvents are suitable to a lesser or greater degree for this purpose, the greatest increase in solubility has been obtained with the addition of octyl

alcohol, particularly 2-ethyl hexanol, and with butyl "Cellosolve" (ethylene glycol monobutyl ether). Of these compounds the 2-ethyl hexanol has proved most satisfactory and is at present available at high purity and relatively low price. Thus, 44% of 2,4-dimethylpentane was dissolved in a mixture of 30% of 2-ethyl hexanol and 70% of 2,3-butanediol at 75° C.

The use of the 2-ethyl hexanol as solubilizer is very advantageous also because its boiling point (183.5° C.) is very near to that of the 2,3-butanediol (182° C.), and because both boiling points are higher than that of the highest boiling component of the mixtures to be separated, viz., xylene. This proximity of the boiling points of both solvent and solubilizer also makes possible the recovery of their mixture for direct reuse upon their common separation on stripping the aromatic hydrocarbons from this solvent mixture. The activity coefficient and relative volatility improvement accorded to the non-aromatic hydrocarbons by the 2,3-butanediol, when used as the solvent, is not reduced to a great extent by the addition of 2-ethyl hexanol if the concentration thereof in the mixed solvents or mixture of solvent and solubilizer is not too high.

A mixture of about 75-85% by volume of 2,3-butanediol and 25-15% by volume of 2-ethyl hexanol has proved satisfactory in every respect. Thus, in the extractive fractional distillation of a mixture of benzene and methylcyclopentane (MCP), which is one of the most difficult of all hydrocarbon mixtures to be separated, the following results were obtained:

Position in Column	Mole percent MCP in Liquid	Relative Volatility, MCP/Benzene	Boiling Point, °C.
Top.....	20	2.3	94
Middle.....	10	2.5	
Bottom.....	0	2.7	126

In the use of pure phenol as the solvent instead of the said mixture of 2,3-butanediol and 2-ethyl hexanol, under the same operating conditions, less favorable results, with respect to the relative volatilities of methylcyclopentane and benzene, could be obtained, and the mixture of butanediol and ethyl hexanol shows definite performance advantages over phenol in separating aromatic from non-aromatics.

Thus, while the butanediols, particularly the 1,3-butanediol and the 2,3-butanediol, and particularly the latter, have proved useful in the extractive distillation of mixtures of aromatic with non-aromatic hydrocarbons to separate them from one another, the solubility of paraffins in these solvents is not very high, and it is therefore proposed by this invention to add a secondary solvent or solubilizer, whereby the undesirable formation of two liquid phases in the extractive distillation section of the distilling column is avoided. Of the octyl alcohols mainly to be considered as solubilizing additives for this purpose, the 2-ethyl hexanol has proved particularly useful, as its boiling point is very close to that of the 2,3-butanediol and as it distinctly increases the solubility of paraffins, which are normally least soluble, in the 2,3-butanediol even when only small additions of the alcohol are made. Thus, a mixture of 75-85 parts of 2,3-butanediol and 25-15 parts of 2-ethyl hexanol improves the relative volatility of the aromatic/non-aromatic system to be treated very considerably and only slightly less than is obtained in the use of the 2,3-butanediol alone. Such a mixture, therefore, is very useful for this purpose. The boiling points of both the primary and secondary solvents, while higher than the boiling point of the highest boiling xylene to be considered, are low enough to allow easy redistillation for purifying purposes.

In order to simplify the separation process, it is advisable though not indispensable, to make use of a close

fraction of the feed stocks for the extractive distillation proper, thus making possible a larger throughput or the use of a smaller extractive distillation apparatus. Thus, naphtha to be subjected to an extractive distillation in accordance with the present invention, is preliminarily subjected to prefractionation separating out respectively a benzene cut and, if desired, a toluene cut of about 10° F. spread in boiling range.

Any type of naphtha or hydrocarbon mixtures containing aromatics and non-aromatics may be treated by the new process, such as cracked naphtha as obtained in the catalytic or pyrolytic conversion of mineral oils, reformed naphtha, polyformed naphtha, straight run naphthas or gasolines containing aromatics, and so on.

Obviously, many modifications and variations of the invention as hereinbefore set forth may be made without departing from the spirit and scope thereof, and, therefore, only such limitations should be imposed as are indicated in the appended claims.

What is claimed is:

1. The method of separating aromatic hydrocarbons from mixtures containing the same and non-aromatic hydrocarbons which comprises subjecting such a mixture to extractive distillation in the presence of a butanediol with addition of octyl alcohol as a solubilizer for increasing the solubility of the non-aromatic hydrocarbons in the butanediol, recovering the liquid fraction comprising said butanediol solvent and said octyl alcohol solubilizer containing extracted aromatics, and stripping the aromatics from said solvent and solubilizer.

2. The method of separating aromatic hydrocarbons from mixtures containing the same and non-aromatic hydrocarbons which comprises subjecting such a mixture to extractive distillation in the presence of 2,3-butanediol solvent and 2-ethyl hexanol solubilizer, recovering the liquid fraction comprising said solvent, said solubilizer and extracted aromatics, and stripping the aromatics from the mixture of solvent and solubilizer.

3. The method according to claim 2 wherein the mixture of said solvent and said solubilizer stripped of aromatics is recycled to the extractive distillation step.

4. The method of separating aromatic hydrocarbons of the group comprising benzene, toluene, and xylenes from mixtures containing the same and non-aromatics in accordance with claim 2.

5. The method of separating aromatic hydrocarbons of the group comprising benzene, toluene and xylenes from mixtures containing them together with naphthenes and paraffins, in accordance with claim 2.

6. The method according to claim 2 wherein the amount of said solvent used is substantially in excess of the amount of said solubilizer.

7. The method according to claim 6 wherein a mixture of 75-85% by volume of 2,3-butanediol and of 25-15% by volume of 2-ethyl hexanol is employed.

8. The method of separating aromatic hydrocarbons from aromatic-bearing naphthas which comprises prefractionating said aromatic-bearing naphthas for concentrating the contents thereof in aromatics, subjecting the aromatic-rich naphtha fraction thus obtained to extractive distillation in the presence of 2,3-butanediol solvent and 2-ethyl hexanol solubilizer, recovering the liquid fraction comprising said solvent, said solubilizer and extracted aromatics, and stripping the aromatics from the mixture of solvent and solubilizer.

9. The method which comprises feeding aromatics containing naphtha to an intermediate portion of a fractional distillation tower while a mixture of 2,3-butanediol and 2-ethyl hexanol is charged to the upper part of said tower, withdrawing a vapor overhead rich in non-aromatic hydrocarbons and a bottoms fraction containing said mixtures concentrated in aromatics.

10. The method according to claim 9 wherein said naphtha is a distillate of a catalytic reformate.

11. The method according to claim 10 wherein said

distillate is a closely cut fraction comprising benzene.
12. The method according to claim 10 wherein said distillate is a closely cut fraction comprising toluene.

13. The method according to claim 10 wherein said distillate is a closely cut fraction comprising one or more of the xylenes.

14. The method which comprises contacting a naphtha reformate fraction, of a boiling range including benzene, with solvent comprising 2,3-butanediol and 2-ethyl hexanol under temperature conditions to effect removal of a vapor overhead having a relative boiling range below that of said benzene and said solvent and the formation of liquid aromatic concentrate rich in benzene, separately distilling said concentrate to recover benzene, and returning the residue comprising said solvent to further 10 contacting of naphtha reformate.
